UNITED STATES PATENT OFFICE.

MARK SPIKINS, OF CHICAGO, ILLINOIS.

ADJUSTABLE PENCIL HOLDER.

Application filed February 15, 1926. Serial No. 88,178.

This invention relates to a pencil holder.

It is well known that some users of lead pencils always desire a long pencil. Others desire a short pencil, while some always desire 5 a pencil of a particular length.

Accordingly it is an object of this invention to provide a pencil holder which is extensible or adjustable so that the desired combined length of the pencil and holder may be obtained by the user, and that as the pencil wears down, the holder may be lengthened so that 10 the proper length is always obtainable.

The invention comprises the novel structure and combinations hereinafter described and 15 more particularly pointed out and defined in the appended claim.

In the accompanying drawings which illustrate a preferred embodiment of this invention and in which similar reference numerals 20 refer to similar features in the different views;

Figure 1 is an elevational view of the pencil holder involving this invention and equipped with a pencil.

Figure 2 is a part sectional and part elevational view thereof.

Figure 3 is a view similar to Figure 2, but showing the holder adjusted in view of a shorter pencil.

Figure 4 is an enlarged sectional view upon 30 the line I-V—IV of Figure 1.

Figure 5 is a fragmentary sectional view of a slight modification.

As illustrative of this invention, there is shown a pair of members 1 and 2 which are 35 connected for longitudinal adjustment, whereby the combined length thereof may be varied. These members are preferably of tubular form and they may be made of any suitable material. In the present instance, 40 they are shown as made of metal.

While the longitudinal adjustment of these members may be effected in various ways, I prefer a threaded connection as illustrated in the drawings whereby relative rotation of the 45 members will produce the desired adjustment, the member 2 being preferably threaded in the member 1.

The free end of the member 1 is designed for containing a pencil 3, and the free end of 50 the member 2 is designed for retaining an eraser 4 which may be screwed into the threaded end of the member 2.

The terminal portions of the member 1 are smooth and not threaded, only an intermediate portion of the member 1 is threaded. 55 These terminal portions are split as indicated at 5 and provided with upwardly offset cam portions 6. Metal bands 7 are slidably mounted upon these terminal portions and when these bands are adjusted over the cam portions 6, they will exert a clamping action to bind the pencil 3 in the holder, and the member 2 in the member 1. These bands are confined between suitably spaced stop ribs 8 and 9 on the member 1. When the bands are 60 shifted against the stop ribs 9, the clamping action will be relieved, as is obvious.

In Figure 5, there is shown a slight modification of the clamping means for clamping the pencil in the holder and for clamping the 70 extension member in adjusted position. It will be noted that the pencil holding member 1^a is externally threaded throughout its extent and that the ends have diverging or sloping surfaces, as indicated at 7^a, to provide a 75 wedging or clamping action when the internally threaded bands 7^a are threaded thereon.

It will be appreciated that this holder can be readily adjusted to provide the proper 80 length, and that it can be cheaply manufactured and assembled, and that as the pencil wears down, it can be lengthened by adjustment to maintain a predetermined length.

I am aware that many changes may be 85 made, and numerous details of construction may be varied through a wide range without departing from the principles of this invention, and I therefore do not purpose limiting the patent granted hereon, otherwise than necessitated by the prior art.

I claim as this invention:

In an extensible pencil holder, a hollow member having a split end with a raised portion, a ring surrounding said split end, a second hollow member in threaded relation with the first member, said ring being shiftable over said raised portion for clamping said members together.

In testimony whereof I have hereunto subscribed my name.

MARK SPIKINS.
